UNITED STATES PATENT OFFICE.

CYRUS HANKINS, OF BALTIMORE, MARYLAND, ASSIGNOR TO THE SYMINGTON COMPANY, OF NEW YORK, N. Y., A CORPORATION OF MARYLAND.

SIDE FRAME.

Application filed November 20, 1925. Serial No. 70,274.

This invention relates to side frames for railway car trucks and more particularly to such frames with journal boxes cast integral therewith and an improved method 5 of casting such frames.

The principal object of the invention, generally considered, is the provision of a cast side frame with integral journal boxes, said frame being efficiently constructed and 10 reinforced so that great strength is secured with a relatively small amount of metal and internal cooling strains are reduced on account of the disposition of the metal therein, weaknesses, ordinarily found at portions 15 of the metal cast adjacent the junction between the green sand mould and baked cores, being minimized by virtue of an improved method of casting.

An object of the invention is the provision 20 of cast side frames for railway car trucks in which the compression and tension members are generally U-shape in cross section and formed with webs and vertically disposed flanges on either side of said webs, 25 such frame being formed with integral journal boxes at the ends thereof and the connection with said journal boxes being reinforced by longitudinal webs or ribs extending from the roof of each journal box 30 to the adjacent portions of the webs of the compression and tension members.

Another object of my invention is the provision of truck side frames in which the frame members are generally U-shape in 35 cross section and integrally connected with journal boxes at the ends of said frames, the connections with said journal boxes being reinforced by triangular gusset portions extending outwardly from the tension member to the upper inner corner of the adjacent journal box.

A further object of my invention is the provision of cast side frames for railway car trucks in which journal boxes are 45 formed integral therewith and in which the design of the upper corners of said journal boxes is improved by eliminating the angular arrangement formerly extending from the outer side wall of the frame members 50 outwardly to the mouth of the journal boxes thereby avoiding difficulties in moulding, the same arrangement being followed at the

upper outer corner of each box so that the journal box cores may be made similar for both sides thereof.

A still further object of the invention is the formation of side frames for railway car trucks in which the compression and tension members thereof are spaced at intermediate portions by bolster column guides 60 and all of said members are formed generally U-shape in cross section with the diagonal end portions of the tension member formed with a lower web and upstanding flanges at the sides thereof, the upper edges 65 of said flanges being reinforced by ribs or beading extending therealong, said beading being thickened or increased in width from the ends of the diagonal end portions of the tension member towards the intermediate or 70 central portions of said diagonal portions thereby eliminating internal cooling stresses by causing the metal in said diagonal portions to cool more uniformly after being cast.

An additional object of my invention is the improvement in the method of casting and particularly the method of casting side frames for railway car trucks in which cores are used for forming external depending flanges or webs on the tension member thereof, said method involving the elimination of substantially transverse lines of weakness between portions of the metal cast 85 respectively adjacent a baked core set in a corresponding portion of a mould and the green sand and the substitution for said transverse lines of weakness of such lines extending diagonally across the casting 90 whereby the strength of said casting at such points is materially increased.

Other objects and advantages of the invention relating to the particular arrangement and combination of the various parts will become apparent as the description proceeds.

Referring to the drawings illustrating a preferred embodiment of my invention, the scope whereof is defined by the appended claims:

Figure 1 is a side elevation, partly in vertical section on the line 1—1 of Figure 2, showing a side frame embodying the various features of my invention.

Figure 2 is a plan view of the side frame illustrated in Figure 1 shown partly in section on the line 2—2 of Figure 1.

Figure 3 is a vertical sectional view on the line 3—3 of Figure 1.

Figures 4, 5, 6 and 7 are detailed sectional views on the correspondingly numbered lines of Figure 1.

Figure 8 is a fragmentary sectional view of the line 8—8 of Figure 2.

Figure 9 is a side view of that portion of a pattern for forming the mould for casting a diagonal end portion of the tension member of the side frame showing particularly core print forming projections improved in accordance with my invention.

Referring to the drawings in detail, like parts being designated by like reference characters, there is illustrated a side frame formed with an upper arch bar or compression member 1, a lower arch bar or tension member 2, between intermediate portions of which are interposed spaced strut or bolster guide column members 3, all of these members preferably being formed generally channel or U-shape in cross section. The compression member 1 comprises an upper web 4 with flanges 5 depending from the side edges thereof, the lower edges of said flanges being strengthened by beading or ribs 6 extending therealong. Likewise the tension member 2 is formed with a lower web 7 and upstanding flanges 8 on opposite sides of said web, the upper edges of said flanges 8 being reinforced by ribs or beading 9 extending therealong, as illustrated particularly in Figures 1 and 5.

The bolster column or strut members 3 are likewise formed with inner webs 10 and outwardly extending flange portions 11 reinforced by ribs or beading 12 extending along the outer edges thereof, the ribs or beading 6, 9 and 12 preferably merging at the ends to form a continuous border or frame around the substantially triangular openings 13 between the compression, tension and bolster guide members. Between the spaced strut members 3 and the intermediate or central portions of the compression and tension members, the usual window or bolster opening 14 is provided, the lower ends of said strut members 3 being offset outwardly as indicated at 15 for the reception of the usual form of truck bolster. The compression member over the bolster opening 14 is substantially horizontal and of approximately the same cross section as over the triangular openings 13 except that the beading or ribs 6 are preferably on the inner sides of the flanges 5 instead of on the outer sides thereof and preferably increase or flare in width or depth toward the bolster columns 3 to form the triangular reinforcements 16. The junctions between reinforcements 16 and 65 the adjacent webs 10 of the strut members

3 are preferably relieved or curved outwardly as indicated at 17 in accordance with usual practice.

Beneath the bolster opening 14, the tension member 2 is substantially horizontal and generally box shape in cross section, that is, the normal U-shape of the member is closed by an upper shelf 18 extending transversely beyond the flange or upright web portions 8 to form a spring seating surface of adequate width in accordance with the usual practice. Said spring seating surface may be provided with bosses 19 of the usual character and the extended edges of shelf portions 18 are preferably braced or reinforced with respect to the flanges or upright portions 8 by transverse substantially triangular reinforcing webs or gussets 20. For preventing the accumulation of water or moisture in the box section of the tension member, one or more drain holes 21 may be provided. The end portions 22 of the shelf or web portions 18 of the compression member on opposite sides of the bolster guide columns are deflected upwardly and tapered to gradually merge into the flanges 8 at points adjacent the lower marginal edges of the openings 13. In a similar way the portions of the web or shelf 18 between said flanges or webs 8 of the tension member are bent upwardly and tapered to merge with the flanges 8 as indicated at 23, the overlying offset portion of the web 10 of each strut or bolster column member 3 being apertured at 24 as indicated particularly in Figure 3.

The tension member immediately below and outwardly of the lower corner of the window opening 14 is preferably reinforced by depending flanges 24 and 25. The depth of these flanges is preferably a maximum substantially coincident with the intersection of the web of the tension member by diagonal lines drawn from the lower corners of the window opening. These flanges 24 and 25 are preferably reinforced adjacent the lower or marginal edges by beading or lips 26 and 27, respectively.

Outwardly toward the ends of the frame the portions of the tension member beyond the strut members 3 extend diagonally upward and outward to meet the slightly cambered or sloping end portions of the compression member 1 adjacent the ends of the frame where the journal boxes 28 are also connected therewith. The flange portions 5 and 8 of the compression and tension members, respectively, merge adjacent said journal boxes and join with the roofs 29 thereof. The web 7 of the tension member intersecting the inner side walls 30 of the journal boxes slightly below the upper inner corners or roofs 29 thereof. The web of the compression member 1 does not directly connect with the roofs 29 of the journal boxes, being cut away as indicated at 31, but the flanges

5 depending therefrom extend to said roofs, the outer edges thereof being curved downwardly to the planes of the outer side walls 32 of said journal boxes as indicated at 33.

6 For strengthening the connection between the side frame and each journal box 28, longitudinal web or rib portions 34 preferably extend from an intermediate or the longitudinal central portion of the web 4 of the

10 compression member 1 to the roof 29 of the adjacent journal box. The outer edges of said webs 34 curve downwardly and outwardly from the termination of the web 4 to the outer edge of the adjacent roof 29

15 while the inner edges of said webs 34 start from the web 4 substantially over the inner wall 30 of the adjacent journal box and continue downwardly and inwardly along a substantially straight line to join with the web

20 7 of the tension member along a substantial portion thereof. Said web 7 of the tension member 2 preferably joins with the inner side walls of the journal boxes 28 slightly below the upper inner corners thereof as indicated at 35. For reinforcing this connection with the journal boxes, triangular web or gusset portions 36 are provided between the outer side of the tension member and adjacent portions of the inner side walls 30

25 of the journal boxes 28, said web preferably extending from the lower edge of the diagonal tension member 2, upwardly and outwardly to the upper inner corner of the adjacent journal box, being offset upwardly

30 for this purpose with respect to the adjacent portions of the web 7 of the tension member 2, thereby effecting an improvement in moulding conditions and making it possible to secure metal of a better quality at that

35 corner of each box roof. The corresponding substantially triangular web portions 37 between the inner side of the tension member 2 and the adjacent portion of the side wall 30 of the journal box, however, preferably

40 lies in the plane of the web 7 of the tension member.

As additional reinforcements between the tension member and the journal boxes, connecting web portions 38 are preferably provided between the lower face or web 7 of the tension member and the adjacent walls 30 of the journal boxes, said web portions 38 extending longitudinally and spaced apart, as indicated particularly in Figure 6, the upper and lower edges of said portions preferably being strengthened by beading or ribs 39 extending therealong. The upper edges of said reinforcements 38 are preferably spaced from the point of union 35 between the web

45 7 of the tension member 2 and the adjacent journal box 28 thereby leaving substantially triangular openings 40.

The angular arrangement between the roof of each journal box and the inner side

50 wall thereof outwardly of the outer flange 7

of the tension member has been improved so that now the roof of the journal box meets the inner side wall thereof at substantially right angles without an intervening diagonal plane therebetween. This change in 70 construction was effected for two reasons: first, to avoid setting an outside core to produce such an angular arrangement of the metal and second, to provide better clearance in setting the cope down over the green 75 sand journal box core. Intermediate of the flanges 8 of the tension member, however, the usual angular arrangement is maintained and this also extends back to the dust guard well 41. The same arrangement is followed 80 at the outer corner of the roof or outer side wall of the box so the journal box cores for the right and left sides thereof may be made similar.

The beading or ribs 9 along the upper edges of the diagonal end portions of the tension member has been thickened or increased in width at the intermediate or central portions. This was done to increase the amount of metal at these points and thereby retard slightly the cooling of the section after casting to render said cooling more nearly uniform with the cooling of the web portion 7 of said section and thereby prevent internal strains from irregular cooling. The section, as constructed in accordance with my invention, now cools without as much tendency to bow out of line thereby eliminating internal cooling stresses because 95 of the restrained ends of these diagonal portions.

Referring now to Figure 9, there is illustrated a portion of the pattern utilized for casting a frame constructed in accordance with my invention. In order to form the flanges 24 and 25 and the connecting webs 38, it is necessary to have core print portions 42, 43, 44 and 45 on the pattern parts 46 and 47. As illustrated, the drag or lower side 47 of the pattern has the core print portions 43 and 45 thereon and the cope or upper side 46 of the pattern has similar core print portions 42 and 44 thereon. These core prints have their ends 48 tapered or extended on diagonal lines, as illustrated, so that the junction between the green sand used for forming the main part of the mould and the baked sand core inserted in the core prints extends along diagonal lines rather than along a substantially transverse line, with just enough draft provided for the withdrawal of the pattern from the mould.

As well known to those skilled in the art, the junction between metal cast adjacent a baked core and that cast adjacent green sand is very imperfect and relatively weak, not only because of the difference in molecular structure of the metal, but because of the offset commonly formed due to not properly matching cores in the mould. The usual

way to end a core print and its corresponding core is indicated by the dot and dash lines extending between upper and lower edges of the core prints. The top view of the core prints are indicated diagrammatically in Figure 1 by dot and dash lines. When side frames are cast utilizing patterns with core prints, as illustrated, the line of imperfect metal along the bottom or web 7 of the diagonal tension portions of the side frame extends along diagonal or broken lines, corresponding with the tapered ends of the core prints rather than substantially directly across the web 7 of said tension member, thereby prolonging the length of imperfect metal between the baked core and green sand mould and extending it over a substantial length of the tension member so that only a small portion of imperfect metal is found in any given section through the tension member.

By virtue of the aforescribed construction, improvement has been effected in the design and method of manufacture of side frames so that the amount of metal employed may be decreased in securing a given strength therein. By virtue of the improved method of casting which method, as will be obvious, is adapted for casting other articles where cores are employed, as well as side frames, greatly improved strength may be effected in such articles, especially portions thereof normally in tension.

Having now described my invention, what I claim is:

1. A car truck side frame comprising a compression member, a tension member, bolster guide columns interposed between intermediate portions of said members, said compression and tension members being generally channel shape in cross section, said compression member being formed with an upper web, and depending flanges at the edges of said web, said tension member being formed with a lower web and upstanding flanges at the edges of said web, the flanges of said compression and tension members merging at the ends of the frame, journal boxes connected to said flanges adjacent the ends of said frame and each formed with a roof with each of said flanges merged with said roof, the connection between said journal boxes and frame being further strengthened by a connecting web extending between and parallel to said flanges and joined with the webs of the compression and tension members and with each journal box roof, the outer edges of said webs sloping downwardly and outwardly from the ends of the compression member web to the outer edges of the journal box roofs, the inner edges of said webs extending in a substantially straight line downwardly and inwardly from the compression mem-

ber web along the web of the tension mem- 65 ber.

2. A car truck side frame comprising a compression member, a tension member, bolster guide columns interposed between intermediate portions of said members, said compression and tension members being channel shape in cross section, said tension member having a lower web and upstanding flanges along the edges of said web, the web of said tension member extending and joining with journal boxes at the ends of the frame slightly below the upper inner corners thereof, said junction being reinforced by substantially triangular web portions extending outwardly from the sides of said tension member in the plane of the web thereof, sloping upwardly and flaring transversely and united with the journal boxes above the plane of the tension member web at substantially the upper inner corners of 85 said boxes.

3. A car truck side frame comprising a compression member, a tension member, bolster guide columns interposed between intermediate portions of said members, said compression and tension members being generally U-shape in cross section and formed, respectively, with upper and lower webs, flanges on the edges of said webs merging at the ends of the frame, journal boxes joined to the compression and tension members at the ends of the frame, the tops of said journal boxes being below the junctions between said compression and tension members, the connection with each journal box being further reinforced by spaced longitudinal webs extending between the lower face of the tension member web and the adjacent journal box wall.

4. A car truck side frame comprising a compression member, a tension member, bolster guide columns interposed between intermediate portions of said members, those portions of the tension member on either side of the bolster guide columns sloping upwardly and outwardly and joining with the compression member at the ends thereof, said tension member being generally channel shape in cross section with a lower web portion and upstanding flanges on either side of 115 said web portion, the junctions between said tension member and journal boxes being further reinforced by vertical web portions extending outwardly from the tension member web to the adjacent wall of a journal box, said webs extending from approximately the side edges of the tension member web and spaced from the junctions between said webs and journal boxes, the upper and lower edges of said reinforcements being strengthened by beading extending therealong.

5. A truck side frame comprising a compression member, a tension member, bolster

- guide column interposed between intermediate portions of said members, said compression and tension members being generally U-shape in cross section and formed respectively, with upper and lower webs, flanges on the edges of said webs merging at the ends of the frame, journal boxes formed with roofs and brass lugs, said roofs sloping from the inner sides of the brass lugs to the side walls of the journal boxes between the flanges of said compression and tension members, said roofs and inner side walls arranged to meet substantially at right angles with each other outwardly of the outer flanges of the compression and tension members.
6. A car truck side frame comprising a compression member, a tension member, bolster guide columns interposed between intermediate portions of said members, said compression and tension members being generally channel shape in cross section and the ends of the tension member being inclined to merge with the compression member at the ends thereof, journal boxes connected at the ends of said frame and formed with roofs and brass lugs, said roofs sloping to correspond substantially with the slope of the inclined end portions from the inner sides of the brass lugs to the edges thereof between the sides of compression and tension members, said roofs and inner side walls arranged substantially at right angles with each other outwardly of the outer side walls of the compression and tension members, said roofs also extending in the same angular relation with respect to the outer side walls of said boxes outwardly of the outer side walls of the compression and tension members so that the journal box cores need not be made right and left.
7. A truck side frame comprising a tension member formed with diagonally disposed end portions having upright portions joining transversely disposed portions, the upper edges of said upright portions being reinforced by transversely disposed beading or flanges which increase in size toward the intermediate portions of said diagonal end portions.
8. A truck side frame comprising a compression member, a tension member, bolster guide columns interposed between intermediate portions of said members, said tension member being formed with upright portions joining transversely disposed portions, said upright portions, along the upper edges thereof, between the ends of the frame and the adjacent bolster guide columns joining with transversely disposed reinforcements which increase in size toward the intermediate portions of said parts of the tension member between the ends of the frame and the adjacent columns.
9. A truck side frame comprising a compression member, a tension member, bolster guide columns interposed between intermediate portions of said members, said compression and tension members being generally U-shape in cross section and formed, respectively, with upper and lower webs, flanges on the edges of said webs merging at the ends of the frame, said flanges extending toward each other and formed with beading along the inner edge thereof, said beading increasing in size toward the intermediate portion of those parts of the tension member between each end of the frame and the adjacent bolster guide column.
10. A car truck side frame comprising a compression member, a tension member, bolster guide columns interposed between intermediate portions thereof, said compression and tension members being generally channel shape in cross section, the compression member being formed with an upper web portion and depending flanges on the edges of said web, said tension member being formed with a lower web portion and upstanding flanges on the edges of said web, the flanges of said compression and tension members merging at the ends of the frame and formed with beading along the free edges thereof, said beading gradually increasing in width toward the intermediate portions of the tension member between the ends of the frame and the adjacent bolster guide column.
11. A car truck side frame comprising a compression member, a tension member, bolster guide columns interposed between intermediate portions of said members, said compression and tension members outwardly of said bolster columns being generally channel shape in cross section and formed, respectively, with upper and lower webs, flanges on the edges of said webs extending towards each other, the portions of the tension member outwardly of the bolster columns sloping outwardly and upwardly with the flanges thereof merging with the compression member flanges, the inner edges of said flanges being reinforced by beading along the outer sides of said flanges, said beading being gradually thickened from the ends of the sloping portions of the tension member toward the intermediate parts of said sloping portions whereby internal cooling stresses in said member are decreased.
12. A truck side frame comprising a compression member, a tension member, bolster guide columns interposed between intermediate portions of said members, said compression and tension members being generally channel shape in cross section, said compression member being formed with an upper web and depending flanges at the edges of said web, said tension member being formed with a lower web and upstanding flanges at the edges of said web, the

flanges of said compression and tension members merging at the ends of the frame, journal boxes connected to said flanges adjacent the ends of said frame and each 5 formed with a roof with all of said flanges merged with said roof, the connection between said journal boxes and frame being further strengthened by a connecting web extending between and parallel to said

flanges and joined with the webs of the compression and tension members and with each journal box roof, the inner edges of said webs extending in a substantially straight line downwardly and inwardly from the compression member web along the web of 10 the tension member.

In testimony whereof I affix my signature.

CYRUS HANKINS.
